(57) **CLAIM**

The ornamental design for a rockerized skate guard, as shown and described.

DESCRIPTION

FIG. 1 is a perspective view of a rockerized skate guard showing my new design;

FIG. 2 is a side view of the rockerized skate guard of FIG. 1, the opposite side view being a mirror image thereof;

FIG. 3 is a front end view of the rockerized skate guard of FIG. 1, the opposite end view being an identical image thereof;

FIG. 4 is a top view of the rockerized skate guard of FIG. 1;

FIG. 5 is a bottom view of the rockerized skate guard of FIG. 1;

FIG. 6 is a cross sectional view of the rockerized skate guard, taken along line 6—6 of FIG. 4; and,

FIG. 7 is a cross-sectional view of the rockerized skate guard, taken along line 7—7 of FIG. 2.

The broken lines shown in FIGS. 2 & 6 represent portions of the design that form no part of the claim.
